United States Patent Office

Des. 191,967
Patented Dec. 19, 1961

191,967

DATA PROCESSING INPUT-OUTPUT DEVICE

David O. Chase, Camillus, and Philip H. Stevens, Syracuse, N.Y., assignors to Smith-Corona Marchant Inc., Syracuse, N.Y., a corporation of New York

Filed Jan. 31, 1961, Ser. No. 63,775

Term of patent 14 years

(Cl. D64—11)

FIGURE 1 is a front perspective view of the data processing input-output device of the present invention; FIGURE 2 is a front elevational view thereof;

FIGURE 3 is a top plan view;

FIGURE 4 is a rear elevational view;

FIGURE 5 is a right side elevational view; and

FIGURE 6 is a left side elevational view thereof.

The dominant features of our design are shown in full lines.

We claim:

The ornamental design for a data processing input-output device, substantially as shown and described.
